UNITED STATES PATENT OFFICE

2,247,025

INSERTING AND REMOVING DEVICE

James A. Jensen, Philadelphia, Pa., assignor to Charles E. Frick, Jr., J. Rodney McCoy, Elsie T. Keller, John H. Jensen and James A. Jensen, co-partners trading as Philadelphia Valve Company, Philadelphia, Pa.

Original application October 29, 1939, Serial No. 300,325. Divided and this application March 26, 1940, Serial No. 325,984

2 Claims. (Cl. 29—86.3)

This invention has general reference to means or devices for removing and replacing articles out of normal manipulatory reach; and more particularly to means for inserting and removing the operative parts of emergency valves, for instance, into and from tank vehicles used for the transportation of inflammable and other liquids.

Specifically, the instant subject-matter is a division from prior application Serial No. 300,325, filed October 29, 1939, by the same applicant, and which matured as U. S. Patent No. 2,212,370, dated Aug. 20, 1940, while the primary object had in view is to furnish a remotely operable device for positive application or removal of the bonnet and associated operative parts, through the manhole, of vehicle tank emergency valves without any necessity of the operator entering such tank.

Another object is to provide a device of the indicated type which is simple and compact in construction, and easily actuatable at a distance from an emergency valve, for example.

Other objects, with ancillary advantages, achieved by this invention will be apparent from or are specifically referred to in the following detailed description of typical embodiments of said invention, as illustrated in the accompanying sheets of drawings, while the features of novelty are more particularly expressed in the concluding claims.

In the drawings:

Fig. 1 is a fragmentary longitudinal section of one end of a truck tank showing the intended use of the inserting-removing device of this invention, in connection with an emergency valve.

Fig. 2 is a broken top plan view of the inserting-removing device.

Fig. 3 (sheet 2) is a fragmentary vertical section through the upper portion of the emergency valve with the inserting-removing device engaged therewith, said Fig. being drawn to a larger scale for the better illustration of otherwise concealed features.

Fig. 4 (sheet 3) is a view similar to the preceding but showing the valve bonnet and associated parts released and ready for lifting out of the tank, as effected by the device of this invention.

Fig. 4 (sheet 2) is a fragmentary section, taken approximately as indicated by the arrows V—V in Fig. 3.

Fig. 6 (sheet 2) is a perspective view of a hook or claw hereinafter particularly explained.

Fig. 7 is a sectional detail somewhat similar to Fig. 5, but showing a modified feature of this invention.

Fig. 8 is an exploded perspective view of the

connected parts shown within the section confines of the preceding Fig.; and,

Fig. 9 is a plan section, taken as indicated by the arrows IX—IX in Fig. 7.

In all the views, corresponding parts are designated by like reference characters.

Referring more in detail to the drawings, and as set forth in the prior patent hereinbefore noted, the numeral 1 designates a broken end portion of a conventional vehicle tank, 2 the man-hole, and 3 the emergency valve; said valve embodying an aperture upper housing 4 with an inner groove 5, for engagement by the tooth portion 6 of spring-influenced circumferentially-spaced latch devices 7 supported by the flange portion 8 of the valve cover or bonnet 9. In the housing 4 is an upwardly-actuable lift-valve 10, under the influence of a spring 11, while the stem 12 whereof extends upwards through the bonnet 9 and is fitted with a rigid bail 13, all of said parts being merely referred to by way of better explaining the inserting-removing device of this invention.

This device, comprehensively designated as 14, 25 comprises a length of tubing or body portion 15, having rigidly secured to one end a somewhat fork-like extension 16 with the wider extremities connected by a bridge 17, in turn embodying a coupler projection 18, for attachment of an appropriate handle 19. Transversely of the fork-like extension 16 is journaled a reel 20, having a crank-handle 21 secured to one end of the axis pin or shaft 22, and whereby said reel is rotatable. Secured to the reel 20 is one end of a flexible or other suitable cable 23 which passes through the body tubing 15, and is trained over a freely rotative sheave 24, journaled on a clamp-bolt 25 having a wing nut 26, said bolt being passed through axially aligned holes 27, respectively in a forked attachment 28 at the other end of the tubular body portion 15, and similar holes 29 in the spaced ears 30 projecting angularly from a cap structure 31, screw-threaded to one end of a tubular section 32. This section 32 is of an interior diameter for free passage over the valve cylindrical bonnet 9 on the valve covering flange 8, into seating engagement with the confronting face of an embossment 33 integral with said covering flange, as readily understandable from Figs. 3 and 4.

Firmly connected to the free end of the cable 23 is a suspension element 34 affording swivel support for an anchorage hook 35, through a bored portion 36 of which the cable 23 is passed before fixture of said element, whereas the claw-

portion 37 is appropriately shaped for easy passage through the valve stem bail 13.

In Figs. 7-9, inclusive, there is shown a modified form of anchorage device 38 for coupling the cable 23 to the valve bonnet 9, said device differing from that previously described in that the suspension element is more in the nature of a "plumb" 39, as clearly shown by the left-hand portion of Fig. 8 and it is provided with a part spherical top 40; whereas the anchorage device 38 is inverted relative to the valve bonnet 9 and is secured to the valve stem 12. The device 38, it is also to be noted, is formed with a forked claw 41 merging inward to a slot 42 of a width to receive the cable 23, while the element top 40 coacts with a complementary rounding 43, provided for its stabilizing reception in the hook 41.

In use of the inserting-removing device 14, it will be readily understood the operator grasps the handle 19 in one hand and releases or "pays-out" the cable 23 by turning the crank 21 to the left sufficiently to lower the anchorage hook 35 below the free extremity of the tubular section 32, and after inserting the device 14 through the tank manhole 2, as shown in Fig. 1, manipulates said device until the hook claw 37 engages the valve stem bail 13; whereupon the crank-handle 21 is turned a few times to the right until the tubular section 32 telescopes over the valve bonnet 9 with its bottom in abutment against the embossment 33, as clearly shown in Figs. 3 and 4. Further rotation of the crank-handle 21 clockwise first pulls the valve 10 above its normal "lift" or until the heels 44 of the latch devices 7 are engaged by the top face of said valve, and rock such devices radially inwards of their respective pivots 45, and thereby release the tooth portions 6 from out of the groove 5, as best understood from Fig. 4. The crank-handle 21 may now be held in the just explained position, while the operator withdraws the device 14 and connected lift valve 19, out through the man-hole 2, for inspection or repair. To replace the lift valve 10, the operation above described will be, obviously, reversed. Attention may here be directed to the fact that by providing the clamp bolt 25 with a wing-nut 26, the angular position of the tubular section 32 may be changed with respect to the body portion 15, in order to accommodate easy manipulation when the valve 3 is otherwise located than proximately below the man-hole 2, said section 32 and body portion 15 then being locked together by simply tightening-up the wing-nut 26.

While there has been described one specific usage of the removing-replacing or inserting-removing device 14, it will be clearly apparent the same is capable of other uses where any article having a bail, eye or the like may be grasped or picked up or set down, from a remote position, by a connecting and compressing tool.

From the foregoing it will be clearly understood that the invention disclosed fully justifies the objects set forth, and it is not desired to limit such disclosure to the exact details of construction shown and explained, for various modifications within the scope of the following claims may occur to those conversant with the art, hence it is intended to include all such changes, or other applications, of the inventive features herein as the state of the prior art permits.

Having thus described my invention, I claim:

1. A placing and removing device comprising a tubular body portion; an angularly adjustable tubular section at one end of the body portion; a fork-like element secured to the other end of the body portion and having the wider part spanned by a bridge; a handle projecting from the bridge; a reel journaled in the fork-like element; a rotary sheave freely mounted at the junction of the tubular body portion with the angularly adjustable tubular section; a flexible cable, having one extremity secured to the reel, passing through the tubular body portion over the rotary sheave and into the tubular section; and means at the free end of the cable for anchorage with the article to be placed or removed, said means being also retractible into the tubular section to prevent its disconnection from the article during manipulation of the device.

2. A device for removing and replacing articles having a bail; said device comprising a tubular body portion having a handle at one end; an angularly adjustable tubular section pivotally connected to the other end of the body portion; a freely rotatable sheave at the pivotal connected tubular portion and section; reeling means journaled to the handle end of body portion; a flexible cable, having one extremity secured to the reeling means, passed through the body portion, over the sheave, and through the tubular section; and a swivel hook at the free end of the cable adapted for retraction within the tubular section.

JAMES A. JENSEN.
